2,467,143

PIPE-LINE STRAINER

Ora N. Mitchell, Hawthorne, Calif., assignor to
 Parkhill-Wade, Los Angeles, Calif., a corpora-
 tion

Application January 20, 1948, Serial No. 3,220

1 Claim. (Cl. 210—164)

1

This invention relates to strainers of the type adapted to be placed in pipe lines for the removal of pipe scale or other solid matter from flowing liquids, vapors or gases.

A purpose of the invention is to provide a form of strainer in which the solids removed from the flowing stream are collected in a pervious receptacle which may readily be removed for cleaning.

A purpose of the invention is to provide a form of strainer which may be constructed at a low cost by welding assemblages of stock fittings.

The structure is illustrated in the two figures of the attached drawings, in which

Fig. 1 is a vertical section through the assembled strainer, and

Fig. 2 is a cross section of the same, taken on the line 2—2 of Fig. 1.

Referring to the figures, the body of the strainer is a plain pipe nipple 10, closed at its upper end by a cap or bull nipple 11, preferably a forging and preferably welded in place. The inlet element 12 is a 90° bend of pipe of the same diameter as the pipe line in which the strainer is to be placed, this element being passed through and welded to the wall of the body in such position that the downwardly looking end is centrally disposed within the body while the outwardly looking end lies in a plane normal to the axis of the body. The outer end of element 12 is provided with a means of attachment to the end of a pipe, as illustrated by the half union 13. On the opposite side of the body an outlet element 14, also a plain pipe nipple, is welded in alignment with the outer end of element 12, the outlet also having a half union 15.

A flange 16 having an outside diameter not less than that of body nipple 10 is welded to the lower end of that element, this flange having a plurality of bolt holes 17. As illustrated, this flange projects inwardly and the ring of bolt holes is within the circumference of the body member, but the flange may project outwardly if preferred, bringing the bolt holes outside the body. Facing this flange is a flat ring 18 of metal to which is attached a cylinder of wire mesh screen. This cylinder is illustrated as consisting of an outer layer 19 of heavy, coarse mesh screen, adapted to resist a high internal pressure, and an inner layer 20 of finer screen of such mesh as will retain the smallest solid particles which it is desired to remove from the fluid. This showing is illustrative only and the cylinder may be composed of a single layer or a plurality of layers of screen, according to the conditions of service. If more than one layer is used, the layers should

2

fit within each other snugly and the upper end of the inner layer should be of such diameter as to be a neat sliding fit over the downwardly looking end of inlet L 12, as at 21.

5 The lower end of body 10 is closed by a plate or blind flange 22 detachably retained in position, as for example by stud bolts 23 and nuts 24. If desired, a central opening 25, closed by a plug not shown, may be provided for draining liquid from the body prior to detaching the plate for cleaning the straining element. The collars shown at 26 and 27 are optional but are convenient for the attachment of pressure gauges, blow-down connections and the like. The lower end 10 of the screen cylinder is permanently attached to the inner edge of ring 18, as at 28. The ring 18 is clamped between plate 22 and flange 17, suitable gaskets not shown being inserted if desired.

10 This structure has material advantages over forms of pipe line strainer heretofore proposed. Being constructed of relatively thin and elastic metal, it is not liable to breakage by sudden changes of temperature and will withstand considerable distortion without damage. The use of thin metal makes the structure amenable to assembly by welding, no machining being required other than for the facing of the flanges. The direction of flow being from the inside of the wire

15 mesh basket outwardly into the body, the solids are collected in the basket and may be withdrawn with it on removal of the bottom plate. This direction of flow also ensures against the collapse of the basket by external pressure in the event of choking of its meshes. As the wire

20 mesh cylinder is seated on the bottom closure plate, there is no tendency to dislodge or displace the cylinder when used with the pressure coming inside, and as there is no accumulation of solids 25 outside the basket, the inner diameter of the body member need be only slightly greater than the outer diameter of the screen cylinder. Finally, the screening cylinder itself may be changed, in case of damage or for the substitution of screen of different mesh, in a minimum of time and at small cost, being a minor element of the cost of the assembly as a whole.

I claim as my invention:

25 A pipe line strainer comprising: a cylindrical body member; a cap closing the upper end of said body; an L passing through the side of said body and fastened therein, one end of said L projecting laterally from said body and the other end directed downwardly therein; a flange attached to the lower end of said body; a plate arranged to be

bolted to said flange and closing said lower end; a ring of metal clamped between said flange and said plate; a cylinder of wire mesh attached at its lower end to said ring and arranged at its upper end to fit snugly around the downwardly directed end of said L; a nipple laterally projected from the wall of said body in axial alignment with the laterally projecting end of said L, and means on the end of each said lateral projection for inserting said strainer in a gap formed in a pipe line.

ORA N. MITCHELL.
